UNITED STATES PATENT OFFICE.

ALVIE C. CRIMMEL, OF HARTFORD CITY, INDIANA.

DESIGN FOR A VENDING STAND.

Application filed March 1, 1928. Serial No. 25,630. Term of patent 3½ years

To all whom it may concern:

Be it known that I, ALVIE C. CRIMMEL, a citizen of the United States, residing at Hartford City, in the county of Blackford and State of Indiana, have invented a new, original, and ornamental Design for Vending Stand, of which the following is a specification, reference being had to the accompanying drawing, forming part thereof.

In the drawings Fig. 1 is an elevational

I claim:

The ornamental design for a vending stand, as shown and described.

ALVIE C. CRIMMEL.
